UNITARY FLAG AND BANNER STANDARD

Harijs J. Francis, Morrill, Nebr.

Application January 23, 1953, Serial No. 332,981

1 Claim. (Cl. 116—173)

1

This invention relates to a flag and banner standard, and more particularly, has reference to a unitary device which is specially adapted to be supported upon a table, platform, or the like, although the construction of said standard does not necessarily limit it to this use.

The standard which I have devised is characterized particularly by its adaptability for supporting a flag either vertically, as a pendant banner, or horizontally in the regular position in which a flag is disposed when being flown.

To this end, the standard constituting the present invention, summarized briefly, includes a vertically disposed staff having a suitable base whereby the staff can be erected upon a table or the like. The staff has a transverse opening near its upper end, and slidable in said opening is a flexible element. The flexible element is connected at its opposite ends to the opposite ends of a support bar, said support bar being adapted to extend along and be connected to one edge of a flag or banner. In one position to which the flexible element is adjusted transversely of the staff, the support bar will be disposed horizontally, crosswise of the staff, and an element secured to the support bar will depend vertically as a banner. In another position to which the flexible element is adjusted, the support bar will be disposed longitudinally of the staff, thus to permit the pennant to be flown as a flag in the regular manner.

One important object of the present invention is to provide a standard of low cost that will be fully portable, so as to be mountable upon a table, platform, or at any other location desired.

Another important object is to provide a standard as stated which, while possessing the desirable characteristics noted above, will yet be capable of manufacture at little or no increase of cost above that required in manufacture of a completely conventional stand.

Another important object is to provide a standard which will be capable of storage in a relatively small area when not in use.

Other objects will appear from the following description, the claim appended thereto, and from the annexed drawing, wherein like reference characters designate like parts throughout the several views, and wherein:

Figure 1 is an elevational view of a standard formed in accordance with the present invention, the parts being shown in position to cause the flag to depend vertically, as a banner;

Figure 2 is a view similar to Figure 1 in which the parts are adjusted to a position for flying the flag, a portion of the flag being broken away;

2

Figure 3 is a sectional view on line 3—3 of Figure 1;

Figure 4 is an enlarged, detail view showing, fragmentarily and in elevation, one end portion 5 of the support bar; and

Figure 5 is an enlarged, fragmentary longitudinal sectional view of the staff, showing the slidable connection of the flexible element thereto.

The reference numeral 10 has been applied generally to a base, said base including a flat, horizontally disposed, rectangular base plate 12 which can be formed of metal or any other suitable material, said base plate being peripherally and dependingly flanged to afford a proper support 15 therefor upon a table, platform, or the like, not shown.

Rigidly secured to the top surface of the base plate 12 is a centrally disposed raised portion 14 of pyramidal shape, said portion being relatively 20 low in height and having a flat top surface. A collar 16, rigidly secured to a staff 18 in closely spaced relation to the lower end of said staff, engages against the top surface of the raised portion 14, the lower end of said staff being fitted 25 removably in a vertical, centrally disposed socket 17 provided in said raised portion.

The staff 18 is formed to a suitable length, and at its upper end, may be provided with a finial 20.

A support bar 22 is substantially shorter in 30 length than the staff 18, and can be formed of a length of tubular metal material or the like (see Figure 4). Extending into opposite ends of and rigidly secured to the support bar are metal loops or eyes 24.

35 A flexible element has been designated by the reference numeral 26, and can comprise a length of rope, cord, etc. At its opposite ends, the flexible element is mounted or otherwise secured to the respective loops or eyes 24. Prior to connection to one of said eyes, however, the flexible element is slidably positioned through a transverse opening 28 formed in the staff 18 adjacent the finial 20 (Figure 5). The flexible element 26 is appreciably greater in length than the support 40 bar 22, as will be readily apparent from Figure 1, and as a result, when the midlength portion of the flexible element is disposed in the transverse opening 28, the support bar 22 will be suspended by said element from the staff, in a horizontal position in which the support bar is disposed crosswise of the staff, as shown in Figure 1.

A flag or banner has been designated generally by the reference numeral 30, and is shown in dotted outline in Figures 1 and 2. The flag or banner is connected along one edge to the support bar 22, the support bar being approximately

coextensive in width with the supported flag or banner. The flag or banner can be connected to the support bar in any manner found suitable, and for example, the flag can be formed with a tubular hem along said edge thereof, said tubular hem receiving the bar 22.

If it is desired that the pennant 30 depend from the standard vertically, as a banner, the element 26 is shifted within the opening 28 to the position shown in Figure 1, as a result of which the edge of the flag that is connected to the bar 22 will be disposed horizontally.

If, however, it is desired that the pennant be supported upon the staff 18 in the regular manner, for flying of the flag (see Figure 2) the element 26 is shifted in one direction within the opening 28, until one end of the element is engaged against the staff. This will cause the bar 22 to extend longitudinally of the staff.

When the bar 22 has been adjusted to this second position thereof, the flexible element 26 can be wound about a lateral projection or hook 32 provided upon the staff 18 a substantial distance below the opening 28. This will eliminate the slack in the flexible element, and will hold both ends of the support bar to the staff, thus to permit the flag 30 to be flown in the regular manner.

Of course, if the flag and banner standard is to be disassembled for storage, it is merely necessary that one end of the flexible element 26 be disconnected from its associated end of the support bar 22, after which the bar and element can be removed completely from the staff 18. The staff can then be detached from its associated base 10, thereby permitting the several parts to be stored together in a relatively small area.

From the foregoing, it will be evident that there has been provided a unitary flag and banner standard in which a flexible element (cord 26) secured to a support bar (22) can be shifted so as to have a pennant depend from the support

bar as a banner or to extend horizontally therefrom as a flag, and a securing means to which the flexible element is secured when it is shifted so as to have the bar carry the pennant as a flag.

It is believed apparent that the invention is not necessarily confined to the specific use or uses thereof described above, since it may be utilized for any purpose to which it may be suited. Nor is the invention to be necessarily limited to the specific construction illustrated and described, since it is only intended that the construction be illustrative of the principles of operation and the means presently devised to carry out said principles, it being understood that the invention comprehends any minor change in construction that may be permitted within the scope of the appended claim.

What is claimed is:

In a unitary banner and flag standard, a staff, a flexible element supported intermediate its ends on said staff to shift transversely thereof, a support bar to which one edge of a banner is connected, said bar being connected at its ends to opposite ends of said element for adjustment to selected positions in one of which positions the bar is disposed transversely of the staff to support a banner and in the other of which positions the bar extends longitudinally of the staff to support a flag, responsive to shifting of the flexible element upon the staff, and securing means provided upon said staff to which the flexible element is attached when the bar is shifted to its position longitudinally of the staff to support a flag.

HARIJS J. FRANCIS.
